Belmont, Mass.

Application March 13, 1943, Serial No. 479,074

10 Claims. (Cl. 109—49.5)

This invention aims to devise an apparatus adapted for use in a great variety of situations to afford a substantial measure of protection for relatively small areas against bombing, or from enemy airplane attack. It is contemplated that this apparatus will be useful, for example, in protecting gun crews, anti-aircraft batteries, aviation ground crews, Army headquarters, and many other units which are not too large for the practical size limitations of an apparatus of this type.

Usually it has been necessary to depend on permanently fixed or stationary coverings of some kind designed to take the force of a bomb or projectile head-on. These shelters rely on the relatively great strength and heavy mass of the material used. There are many situations, however, in which neither the time nor the opportunity to erect shelters of this type is available, and where there is, consequently, a need for some protective apparatus that can be moved into position quickly and moved on again when the need for it in that particular location has disappeared. It is one of the objects of this invention to devise an apparatus of this character.

To this end it is a further object of the invention to devise a protective apparatus which will not depend so much on weight and strength of material as upon the effect of less weight revolving at a high speed. In the preferred construction the material is so disposed as to deflect or explode a bomb at a considerable distance from the protected area, and also to afford a secondary means of protection against flying fragments, shrapnel, flash, and the like.

The nature of the invention will be readily understood from the following description when read in connection with the accompanying drawings, and the novel features will be particularly pointed out in the appended claims.

In the drawings,

Figure 1 is a side elevation, with some parts broken away, of an apparatus embodying the invention;

Fig. 2 is a plan view, somewhat diagrammatic in character, of the revolving arms and the upper part of the supporting means for them;

Fig. 3 is a plan view of the upper end of the revolving unit;

Fig. 4 is a vertical, sectional view taken approximately on the line 4—4, Fig. 3;

Fig. 5 is a sectional view on the line 5—5, Fig. 4;

Fig. 6 is an edge view of a portion of the supporting head structure at the upper end of the shaft;

Fig. 7 is a horizontal, sectional view on the line 7—7, Fig. 1;

Fig. 8 is a vertical, sectional view through the supporting means for the lowermost series of revolving arms;

Figs. 9 and 10 are sectional views on the lines 9—9 and 10—10, respectively, of Fig. 8;

Figs. 11 and 12 are edge and plan views, respectively, showing, on a larger scale, features of the lower series of arms;

Fig. 13 is a side view of the mechanism for supporting and adjusting the shaft on which the arms are mounted, some parts being broken away in order better to illustrate details of construction;

Fig. 14 is a sectional view taken approximately on the line 14—14 of Fig. 13;

Fig. 15 is a similar view taken on the line 15—15 of Fig. 14; and

Fig. 16 shows a detail of the adjusting mechanism illustrated in Fig. 13.

The construction shown in the drawings comprises a base 2, Fig. 1, which may or may not be mounted for vertical adjustment, as desired.

25 Mounted on this base for adjustment about both vertical and horizontal axes, as will later be explained, is a turn-table 3 supporting a structural steel frame work which is indicated, in general, at 4. At its upper end this structure supports an

30 electric motor 5 which is provided with an elongated shaft 6 extending upwardly above the motor for a substantial distance and on which hub structures 7 and 8 are secured. These two hub members carry upper and lower sets of arms 9

35 and 10, respectively. The arms of both series are of a flexible nature, but they differ very materially in their construction and in the functions which they are adapted to perform.

These two sets of arms are designed, when they

40 are revolved rapidly around the shaft 6, to form a protective screen for the area below them. It is contemplated that the upper set of arms will be made of solid, relatively heavy, articulated members flexibly connected together and capable

45 of deflecting or exploding a bomb coming in contact with them. The lower arms 10 are considerably wider and more fan-shaped than are the upper arms, as shown in Fig. 2, and they are designed to provide a much tighter screen than do

50 the arms 9 so as to afford good protection against machine gun fire, shrapnel, and the like. It is practical to make arms twenty or twenty-five feet, or more, in length so as to protect a circular area of twice that diameter directly below them.

55 As best shown in Figs. 2 to 5, inclusive, each of

the upper arms 9 consists of a chain 11 carrying a hook 12 at one end, by means of which it is secured to a cross-pin 13 forming part of a block 20 which is set into a slot in the edge of the hub structure 7, and a series of heavy metal sleeves 14 threaded on said chain and preferably having ball and socket jointed connections with each other. At the outer end of the chain a disk-like body 15, Fig. 2, is secured thereto and holds the other members from being thrown off the chain. Any desired number of these relatively heavy arms may be used, eight being shown in the construction illustrated in Fig. 2. Preferably the members 14 are provided with sharp edges, as shown in Fig. 5, to assist in performing the deflecting action above referred to.

The hub structure 7 comprises a collar 16, Fig. 4, pinned to the shaft 6, a plate-like section 17 secured to the collar, and a cap member 18 bolted or riveted to the part 17. These members clamp in position a series of the blocks 20 above referred to, and bars 21 lock the blocks against movement out of the sockets in which portions of each rest in the part 18, while another bar 22 in front of the bar 20 prevents the hook 12 cooperating with it from swinging upwardly to any great extent above a horizontal position. The upper member 18 also includes a dome portion fitting over the top of the shaft 6, and it may be equipped with arms, such as those shown at 23, or other parts designed to assist in deflecting bodies which may strike them.

The lower arms 10 preferably are made up by welding sections of wire cable into substantially the form shown in Figs. 2, 11 and 12. Each arm includes a heavy central strand 24 of wire rope with an outer binding strand 25 of the same material, and intermediate horizontal strands 26 of filling material, usually of smaller diameter, which may be interwoven with the strands 24 and also, if desired, with those shown at 25. In order to secure these arms 10 in their operative positions, each is equipped at its inner end with an eye formed around a grooved roll 27, Figs. 8, 9 and 10. Each of these rolls is mounted on a short shaft 29, the ends of which are supported in a pair of bearing blocks 28, as best shown in Fig. 10. The hub member 3 on which these arms are supported comprises a cap 30, Fig. 8, and a lower member 31, the latter being pinned to the shaft 6 which, if desired, may be made in two sections divided at the center of the hub, as shown in Fig. 8, in which event the two hub members will be pinned to the two respective sections. Both of these members are of disk-like form, and the lower member has a series of slots 32 formed in its edge to receive the rolls 27, the walls of these slots being notched, as indicated at 33, to take the bearing blocks 28. Screws or bolts secure the latter in place.

This arrangement, therefore, supports the arms for swinging movement about the individual axes of their respective rolls 27 so that when the apparatus is idle and the shaft is in its upright position, these arms will lie beside the shaft or the frame work 4. The two sections of the hub are riveted or bolted together, and the entire weight of this hub structure and the load which it carries, is borne by the frame structure 4, a set of anti-friction bearings 34 being interposed between these parts.

As above stated, the entire rotating assembly is mounted for adjustment about both a vertical and a horizontal axis so that it may be inclined and "trained" into the desired position to afford

maximum protection against the attacking force. For this purpose the turn-table 3 is made integral with, or is secured rigidly to, the ball 35, Figs. 1, 13 and 14, and this ball is supported in a socket 36, Fig. 14, formed in the base 2, and preferably is mounted on anti-friction bearings. A horizontal shaft 37 extends through the center of the ball and carries pinions 38 and 38' near its opposite ends which run on a circular rack 40 supported on the upper edge of the socket section of the base 2. Thus this shaft forms a horizontal axis about which the turn-table 3, and the shaft carried thereby, may be tipped into different angles of inclination. In order to make this adjustment, an arcuate rack 41, Fig. 13, is set into the sphere 35 and pinions 42 mesh with said rack, these pinions being secured fast on a shaft 43, Fig. 16, which also has a worm gear 44 secured thereto and meshing with a worm 45, Fig. 13, fast on a shaft 46 which is connected through spur gears and another shaft with a hand wheel 47. Consequently, by revolving this hand wheel the ball 35, and the parts mounted thereon, may be turned around the shaft 37 into various angular positions. The worm and worm gear, being irreversible, will hold the assembly in any desired position of adjustment.

When it is desired to adjust the turn-table 3, and the parts mounted thereon, around a vertical axis, this operation may be performed by revolving the hand wheel 53 and, consequently, the shaft 37. The pinion 38 is pinned to the shaft, while the other pinion 38' is free on the shaft. Consequently, such rotation of the pinion 38 operates through its engagement with the rack 40 to swing the turn-table around a vertical axis passing through the center of the ball 35. A brake mechanism is operatively associated with this shaft to lock it against accidental rotative movement. As best shown in Fig. 15, this mechanism comprises two arms 48 fulcrumed on the rod 54 and carrying inwardly directed pins arranged to engage the outer surface of the shaft 37 on which the hand wheel 53 is secured. Another shaft 50, Fig. 15, mounted transversely to the shaft 37, carries right and left-hand screw-threaded sections engaging the internally threaded lower ends of the arms or levers 48. The latter shaft also carries a hand wheel 51 and, consequently, by revolving this hand wheel in the proper direction, the arms 48 may be moved toward each other until the pins which they carry are caused to grip the shaft 37 securely. A reversal of these operations releases the brake. The same kind of a brake can be used on the shaft 46, if desired.

For the purpose of giving the ball 35 the lateral stability necessary to support the shaft 6 and its load in different inclined positions, the socket section of the base 2 is provided with horizontal grooves *a*, Fig. 13, and the ball 35 has two heavy brackets 52-52 secured rigidly to it and provided with inwardly projecting ribs *b* which extend into, and have a running fit with, the walls of the grooves. Thus any tendency of the ball to rotate in the socket is effectually prevented by those parts which connect the ball with the brackets and the interlocked relationship of the brackets with the base 2.

In the event that it is desired to adjust the entire apparatus above described into different elevations, such an arrangement as that shown in Figs. 1 and 7 may be used. It comprises a bed piece 55 having three legs like those shown in Fig. 1 at 56 and 58 radiating therefrom and se-

cured rigidly thereto by removable pins 60, Fig. 7, so that they cooperate with the part 55 to provide a broad lateral bearing. Mounted to slide vertically through this base are two racks 61, toothed on the surfaces which face each other, and meshing with two sets of pinions mounted, respectively, on the shafts 62 and 63. An intermediate shaft 64 carrying a hand wheel 65 and mounted in the base piece parallel to the above-mentioned shafts, carries a worm 65' meshing with a worm wheel 66, fast on a shaft which is geared to both the shafts 62 and 63. Consequently, by revolving this hand wheel the entire structure may be moved up or down and it will be held in its adjusted position by the worm and worm gear, these two parts being designed to accomplish this result. It will, of course, be understood that in using this adjustment a shaft or elevator well 67, Fig. 1, must be provided to accommodate the racks 61.

This entire apparatus may be shipped to any point where protection is desired for a relatively small area, such as any of those above mentioned, and it may be there set up and put into operation only when needed. Normally the upper arms 9 will hang down idly or be lashed against the shaft 6, and the lower arms 10 also may be lashed against the frame work with their springs 69 bearing against the bumper reinforcing piece 68 shown in Fig. 1. But when the protection which the apparatus affords is desired, the motor 5 is started up, and as it gains speed, the arms 9 and 10 will rise until finally they assume approximately horizontal positions, as illustrated in Fig. 1. The motor should have sufficient power to revolve the arms very rapidly. If bombs of the smaller sizes drop into the path of movement of the heavier set of upper arms 10, the latter will be practically certain to strike them and either deflect them or explode them. Smaller bodies striking the apparatus from overhead, such as shrapnel, machine gun bullets, or even small bombs, will be caught and deflected by the much larger fan-shaped arms of the lower set 10. Thus the apparatus will afford a very substantial degree of protection against hazards of those types more likely to be encountered from overhead. At the same time the apparatus can be adjusted in the manner above described to point it toward the direction from which the attack comes so that it can be used most effectively.

Obviously this apparatus does not afford any substantial degree of protection against very heavy bombs, and it is not intended for that purpose, but rather to provide a more mobile way of obtaining that protection customarily afforded by fixed shelters of some type. This apparatus can be readily taken down, moved to another location, and re-assembled, these operations requiring relatively little time. The ability to separate the two sections of the shaft 6, as above described, is useful in accomplishing this object. It will also be understood that while an electric motor is shown at 5 to drive the shaft 6, other forms of motors can be substituted for it and other methods of driving can be used. These and other modifications can be made within the spirit and scope of the invention.

All outside surfaces of the complete apparatus which would be visible at any time from overhead could be painted to blend in with the ground, background, ocean, desert, or the like, as viewed from overhead. In other words, the apparatus would be camouflaged. This would not only eliminate the white or grayish looking "spin"

effect, but the camouflaging could be done in such a way that the thing protected, such as a gun position, Army headquarters, or the like, would be hidden from overhead view. For instance, the apparatus could be used to mask very completely an isolated gun position, or if a plane-carrier had several of these devices installed on it at various parts of the top side of the ship, they could be made to contribute very substantially to camouflaging the ship and the planes mounted on it. This feature, however, is additional to the primary object of protection.

Having thus described our invention, what we desire to claim as new is:

- 15 1. A protective apparatus of the character described, comprising the combination of a shaft, means for revolving said shaft, means for supporting said shaft in a substantially upright position, and a series of flexible metallic arms mounted on said shaft at approximately a common level to swing into radiating positions relatively to the shaft and serving, when said shaft is revolved rapidly, to form a protective screen for the area immediately below them, said arms being free to drop into collapsed positions closely beside said shaft when the shaft stops revolving.
- 20 2. A protective apparatus according to preceding claim 1, in which the supporting means for said shaft is operable to adjust said shaft into various angles of inclination.
- 25 3. A protective apparatus according to preceding claim 1, in which the supporting means for said shaft is operable to adjust said shaft about both horizontal and vertical axes to shift the protective screen formed by said arms into various relationships to the area protected by it.
- 30 4. A protective apparatus according to preceding claim 1, in which said supporting means includes parts adjustable vertically to change the elevation of said shaft and said arms.
- 35 45 5. A protective apparatus of the character described, comprising the combination of a shaft, means for revolving said shaft, means for supporting said shaft in a substantially upright position, and two series of arms mounted on said shaft, one above the other, the arms of each series being mounted on the shaft at a common level and adapted to swing into approximately a right angle relationship to the shaft and the arms of one at least of said series being of a flexible metallic construction.
- 50 55 6. A protective apparatus according to preceding claim 5, in which the arms of the upper series are of relatively solid and metallic but articulate construction while those of the lower series are of greater width circumferentially and are more flexible in character but are of a metallic nature.
- 60 65 7. A protective apparatus of the character described, comprising the combination of a shaft, means for revolving said shaft, means for supporting said shaft in a substantially upright position, a plurality of series of metallic arms mounted on said shaft with one series above another, the arms of the upper series being adapted to deflect a body falling into them and those of the lower series providing, when in operation, an approximately continuous protective screen and means pivotally supporting all of said arms for swinging movement, when revolved rapidly, into raised and extended positions and said arms being free to drop into collapsed positions closely beside said shaft when the shaft stops revolving.
- 70 75 8. A protective apparatus according to preceding claim 7, in which the arms of the upper

series comprise solid articulated and flexibly supported members adapted to develop a high degree of momentum, and the arms of the lower series are of somewhat fan-shape with their larger ends remote from said shaft.

9. A protective apparatus of the character described, comprising a turn table, a shaft mounted on said turn table and normally extending upwardly therefrom, means carried by said turn table for revolving said shaft around its own axis, a series of metallic arms mounted on said shaft to swing, under the influence of centrifugal force produced by the rapid rotation of the shaft, from collapsed positions closely beside said shaft into radiating positions relatively to the shaft,

5 whereby said radiating arms form a protective screen for the area immediately below them, and means supporting said turn table for adjustment both around a horizontal axis to adjust the said shaft into different angles of inclination and also to swing said shaft bodily around a vertical axis to point the shaft in different directions.

10. A protective apparatus according to preceding claim 9, in which said supporting means for the turn table is operable to adjust said turn table and the shaft mounted on it into different elevations.

SYDNEY T. FARRELL.
FREDERICK L. FARRELL.
